UNITED STATES PATENT OFFICE.

FRANK P. HARRIS, OF CRANFORD, NEW JERSEY.

FIRE-EXTINGUISHING COMPOUND.

1,190,160.

Specification of Letters Patent.

Patented July 4, 1916.

No Drawing.

Application filed June 2, 1914. Serial No. 842,374.

To all whom it may concern:

Be it known that I, FRANK P. HARRIS, a citizen of the United States, residing at Cranford, in the county of Union and State of New Jersey, have invented certain new and useful Improvements in Fire-Extincting Compounds, of which the following is a specification.

This invention relates to an improved compound for extinguishing fires of a refractory nature, such as fires caused by burning petroleum oil, benzin, gasoline, and similar materials, and its novelty consists in the ingredients of the compound.

The principle of application of the compound consists essentially in establishing at the seat of combustion a lingering blanket of a dry, heavy combustion-arresting vapor, which is generated by throwing upon the fire a liquid capable of being volatilized by the heat of the fire, or of forming a film or blanket that shall further evolve vapors or by its own action as a retardant, smother the flames, and producing the desired heavy, gaseous blanket after reaching or during the course of its passage toward the fire.

The compounds are further applicable to the extinguishing of fires caused by electricity and fires around electrical machinery where the use of water would cause serious damage to the machinery and possible injury to the user.

The compound, used in forming the gaseous blanket referred to, is preferably a mixture of acetylene haloid derivatives, such as acetylene tetrabromid, diluted by the addition of other compounds, such as carbon tetrachlorid, the function of which compounds is that of a non-inflammable vehicle to convey the acetylene compound to the point of service.

I preferably form the compound by taking a suitable quantity of such a vehicle, for instance, carbon tetrachlorid, adding thereto a haloid acetylene derivative, such as acetylene tetrabromid so that the acetylene derivative is about 10% by weight of the total mass. To the compound so formed there is preferably added a compound, such as trichlorethylene, to reduce the freezing point of the resultant liquid. The fluid so formed should be kept in a suitable container, and be maintained therein under pressure either by the use of liquid carbonic acid or compressed air or other vapors or fluids, which

will give the necessary ejecting force from the container when the compound is applied. Or application of the fluid may be had by mechanical means through the agency of a properly made device that shall expel the fluid. When used it is forced in a stream toward the fire and its vapors, being both volatile and heavy, there is produced a blanket of dry incombustible vapor overlying the burning material, and shutting off the supply of air, thus effectually extinguishing the blaze by a process of smothering. This blanket, moreover, is of such a nature that it does not mingle with the vapors produced from the combustion of the burning material and the non-combustible vapors formed have such a high specific gravity that they are not materially dissipated by the force of the draft created by such combustion as might be the case with lighter vapors.

When the fluid is delivered above the burning liquids, such as gasoline or oil, the gaseous blanket immediately settles over the surface and does not materially scatter the liquid, but remains over the surface a considerable time as a heavy blanket which is incombustible and a non-supporter of combustion and an extinguisher of flame and thereby smothers the blaze.

I do not wish to be understood as confining myself to the use of the particular ingredients mentioned for the acetylene compound or to the particular mixtures added to such compound, although from practical experience, I have found that the use of certain mixtures, such as acetylene tetrabromid with a proper vehicle, such as carbon tetrachlorid which is itself non-inflammable with or without the addition of another compound, such as trichlorethylene to aid in the reduction of the freezing point of the resulting liquid is more effective than that of the usual elements entering into fire extinguishing fluids.

I have also found that the addition of a compound having a bromin radical in its structure, such as bromoform materially adds to the efficiency of the liquid for fire extinguishing purpose, and also aids the reduction of the freezing point. The preferred ingredients described have also exceptional advantages in that they are both non-poisonous and volatile and of a nature that does not in any way injuriously affect the objects upon which they fall, there be-

ing no residue left and so far as known to me, no injurious affect to any fabric or material.

The fluid above described is peculiarly adaptable for the extinguishing of fires from burning petroleum distillates, such as gasolene, kerosene and lubricating oils, from the fact that the preferred form of the fluid is miscible with such liquids, whereby a stream of the extinguishing compound or fluid, delivered upon the surface of such liquid in a state of ignition would not by the force of impact penetrate through the liquid to a point beneath its surface and thus lose its efficiency. On the contrary, it is obvious that being so miscible with liquids of this class, it cannot pass through a layer of such liquid and therefore its extinguishing effect will be promoted.

What I claim is:

1. A fluid adapted for use in extinguishing fires, comprising a haloid derivative of acetylene in a non-combustible liquid vehicle, in combination with a suitable compound adapted to reduce the freezing point of the mixture.

2. A fluid adapted for use in extinguishing fires comprising a haloid derivative of acetylene in a non-combustible liquid vehicle, a compound, having a bromin radical in its structure, and a suitable ingredient

adapted to reduce the freezing point of the mixture.

3. A fluid adapted for use in extinguishing fires comprising acetylene tetrabromid and carbon tetrachlorid.

4. A fluid adapted for use in extinguishing fires comprising acetylene tetrabromid, carbon tetrachlorid and trichlorethylene.

5. A fluid adapted for use in extinguishing fires comprising acetylene tetrabromid, carbon tetrachlorid and a noncombustible liquid adapted to reduce the freezing point of the mass.

6. A fluid adapted for use in extinguishing fires comprising acetylene tetrabromid, carbon tetrachlorid, trichlorethylene and bromoform.

7. A fluid adapted for use in extinguishing fires comprising a haloid derivative of acetylene a non-combustible liquid vehicle therefor miscible with petroleum distillates, a compound having a bromin radical in its structure, and a noncombustible liquid adapted to reduce the freezing point of the mass.

In testimony whereof I affix my signature in presence of two witnesses.

FRANK P. HARRIS.
